CONVERTIBLE COIN ROLLING MACHINE

Max E. Schneider, San Antonio, Tex.

Application December 12, 1947, Serial No. 791,427

6 Claims. (Cl. 93—2)

1

This invention relates to devices for applying wrappers to rolls of coins wherein the coins are rolled and wrapped by hand, and in particular a base with an inclined upper surface having adjustable coin holding means and guides for retaining the coin holding means in position upon the base as a wrapper is rolled around the coins.

The purpose of this invention is to expedite wrapping rolls of coins by providing a device in the form of a jig in which coins may readily be positioned, clamped in a roll, and wrapped while held by the clamping means.

Various devices have been provided for stacking and arranging coins for rolling but it is customary to remove the rolls of coins with the rolls gripped between the thumb and forefinger so that the rolls may be positioned upon a wrapper or the like and in this step the rolls sometimes bulge or the coins slide so that it is necessary to rearrange the coins in the roll. With this thought in mind this invention contemplates a small unique machine on which coins may be rolled in which the coins are clamped and wrapped while held by the clamping means and without being removed from the machine.

The object of this invention is, therefore, to provide a comparatively small stand on which coins may be arranged in rolls wherein the rolls of coins are positioned on wrappers and wrapped on the upper surface of the stand.

Another object of the invention is to provide a stand which facilitates wrapping rolls of coins in which the parts may readily be adjusted for coins of different denominations.

Another object of the invention is to provide a stand on which rolls of coins may readily be wrapped in which the coins are clamped in rolls as they are wrapped and from which the wrapped rolls may readily be removed.

A further object of the invention is to provide a coin roll wrapping stand which is of a simple and economical construction.

With these and other objects and advantages in view the invention consists of the new and novel combination, construction, and arrangement of parts as hereinafter more fully described, set forth in the claims appended hereto, and disclosed in the accompanying drawings, forming part hereof, wherein:

Figure 1 is a plan view of the stand illustrating the position of a roll of coins thereon before being rolled, in dotted lines.

Figure 2 is a view showing a side elevation of the machine.

Figure 3 is a view showing an end elevation

2

of the stand looking toward the lower or starting end thereof.

Figure 4 is a longitudinal section through the machine taken on line 4—4 of Figure 1.

Figure 5 is a cross section through the stand taken on line 5—5 of Figure 2.

Figure 6 is a cross section through the low end of the stand taken on line 6—6 of Figure 2.

Figure 7 is a cross section through the stand taken on line 7—7 of Figure 2.

Figure 8 is a detail showing a plate for adjustably mounting a coin holding roller on the stand.

Figure 9 is a detail taken on line 9—9 of Figure 2 showing the upper guide frame with parts omitted.

Figure 10 is a detail showing a section through the outer end of the stand taken substantially on line 4—4 of Figure 1, with the parts on an enlarged scale and with parts broken away.

Referring now to the drawings wherein like reference characters indicate corresponding parts the coin rolling machine of this invention includes a stand 10, a guide frame having sides 11 and 12, and a mounting plate 13.

The stand 10 is formed with an inclined upper surface 14 with sides 15 and 16, and a low end 17 and a high end 18. The lower edges of the sides are provided with flanges 19 and 20 and suction cups 21 are mounted in the flanges as illustrated in Figure 6 whereby the stand will be held in operative position upon a flat surface while coins are being rolled thereon.

The sides 11 and 12 of the guide frame are connected at the lower end by a roller 22, and at the upper end by a rod 23, the ends 24 and 25 of which are journaled in the upwardly extending ends 26 and 27 of a U-shaped frame 28 that is mounted on the upper surface 14 of the stand by screws 29, as shown in Figure 4, or by rivets 30 as shown in Figure 10. The rod 23 is provided with a tongue 31 that is held with an adjusting screw 32, and the screw is provided with a spring 33 and a lock nut 34. The spring 33 urges the tongue 31 upward thereby holding the roller 22 downward, and by turning the screw 32 by the thumb nut 35 the tongue may be drawn downward so that the roller 22 may be adjusted upward wherein the guide will accommodate coins of larger diameters. The sides 11 and 12 are provided with slots 36 and 37 with the ends connected at the lower end to the roller 22 by bars 38 and 39, as shown in Figure 9, and the roller is mounted in the bars by pins 40 and 41. The upper ends of the sides are rigidly connected

to the rod 23 by posts 42 and 43, and it will be noted that the lower edges of the sides extend downwardly overlapping the sides of the stand 10.

The mounting plate 13 is longitudinally slideable on the upper surface 14 of the stand and is held to the stand by a thumb screw 44 that extends through an opening 45 in the plate and a slot 46 in the stand, and the inner end of the screw is secured by a lock nut 47 which is prevented from turning by a lug 48 on the under side of the upper surface 14. The ends of the mounting plate 13 are provided with guide posts 49 and 50 and bearings 51 and 52 are provided in the inner edge in which a roller 53 is journaled by pins 54 and 55 at the ends thereof. The roller 53 is positioned to coact with a slot 56 in the upper surface 14 of the stand so that coins may be set against the surface thereof with the upper part of the coins contacting the roller 22. The rollers 22 and 53 are, therefore, adjustably mounted whereby the device may be set to accommodate coins of different sizes.

The coins may be clamped on the stand by thumb screws 57 and 58 which are threaded in bearings 59 and 60, that are slidably held in the slots 36 and 37 of the sides of the guide frame wherein with coins clamped between the thumb screws the coins may be rolled along the upper surface of the stand. The bearings 59 and 60 are provided with annular recesses 61 and 62 and the inner ends of the screws are provided with gripping collars 63 and 64 that contact the coins.

With the parts arranged in this manner a coin wrapper may be placed upon the upper surface 14 of the stand and the coins counted and positioned to form a roll, as shown by the dotted lines in Figure 1, with the lower edges contacting the rollers 22 and 53. The thumb screws 57 and 58 may then be tightened against the ends of the coin roll and by turning the thumb screws with the thumbs and forefingers of the hands the roll of coins with the wrapper may be rolled on the rollers. After the wrapper is rolled around the roll of coins the thumb screws may be unscrewed and the ends of the wrapper crimped over the ends of the coins, or the roll may be twisted diagonally and removed and then the wrapper crimped at the ends.

The stand is adapted for coins of different denominations and sizes as the rollers 22 and 53 may be adjusted to coins of larger or smaller diameters, and as the roller 22 is adjusted the slots in the sides of guide frame are also adjusted to the proper elevation in relation to the stand.

The bearings 51 and 52 at the corners of the plate 13 in which the roller 53 is mounted and also the bearings 59 and 60 in which the screws 57 and 58 are threaded may be formed of plain iron nuts and the nuts may be welded to the plates or other parts, and the nuts 51 and 52 may be bored out to form bearings, as may be desired.

It will also be noted that after the roll of coins is assembled the roll of coins with the wrapper is rolled on the rollers at the lower end of the stand by hand, and the thumb screws are only moved up in the slots to take out the completed wrapped roll of coins.

It will be understood that modifications may be made in the design or arrangement of parts without departing from the spirit of the invention.

What is claimed is:

1. A coin rolling machine comprising a stand 75 having an inclined upper surface, a guide frame

having sides with aligned longitudinally disposed slots therein pivotally mounted on the stand adjacent the upper end thereof, a coin holding roller carried by the lower end of the guide frame, a transversely disposed roller positioned to coact with the coin holding roller for positioning coins on the stand, and coin clamping means slidably mounted in the slots in the sides of the guide frame whereby a roll of coins secured between the clamping means are rolled upwardly over a wrapper on the said inclined upper surface for positioning the wrapper around the roll of coins.

2. A coin rolling machine comprising a stand 15 having an inclined upper surface, a guide frame having sides with aligned longitudinally disposed slots therein pivotally mounted on the stand adjacent the upper end thereof, a coin holding roller carried by the lower end of the guide frame, means adjusting the elevation of the lower end of the guide frame and roller carried thereby in relation to the upper surface of the stand, a transversely disposed roller positioned to coact with the coin holding roller for positioning coins on the stand, and coin clamping means slidably mounted in the slots in the sides of the guide frame whereby a roll of coins secured between the clamping means are rolled upwardly over a wrapper on the said inclined upper surface for positioning the wrapper around the roll of coins.

3. A coin rolling machine comprising a stand 25 having an inclined upper surface, a guide frame having sides with aligned longitudinally disposed slots therein pivotally mounted on the stand at 35 a point adjacent the upper end thereof, a coin holding roller carried by the lower end of the guide frame, a transversely disposed roller positioned to coact with the coin holding roller for positioning coins on the stand, means adjustably mounting the said transversely disposed roller on the stand, and coin clamping means slidably mounted in the slots in the sides of the said guide frame whereby a roll of coins secured between the clamping means are rolled upwardly over a wrapper on the said inclined upper surface for positioning the wrapper around the roll of coins.

4. A coin rolling machine comprising a stand 40 having an inclined upper surface, a guide frame having sides with aligned longitudinally disposed slots therein mounted on the stand, a coin stop 50 carried by the lower ends of the sides of the guide frame, a coin holding roller parallel to the stop and positioned to coact therewith for positioning coins on the stand, means adjusting the position 55 of the coin holding roller on the stand, and thumb screws threaded in bearings slidably mounted through the bearings in the slots in the sides of the guide frame.

5. A coin rolling machine comprising a stand 60 having an inclined upper surface, a guide frame having sides with aligned longitudinally disposed slots therein positioned on the stand, means pivotally mounting the guide frame on the stand at the upper end thereof, a thumb screw for adjusting the position of the guide frame, a spring coacting with the thumb screw urging the guide frame against the thumb screw, a coin holding roller carried by the lower end of the guide frame, a transversely disposed roller positioned to coact 65 with the coin holding roller to position a roll of coins on the stand, means adjusting the position of the transversely disposed roller longitudinally of the stand, bearings slidably mounted in the slots in the sides of the guide frame, and 70 thumb screws threaded in the said bearings.

6. In a coin rolling device, a stand having an inclined upper surface with a transverse slot therein, a rectangular-shaped frame having sides with longitudinally disposed slots therein, means pivotally mounting the frame on the stand, means adjusting the elevation of one end of the frame, a coin holding roller carried by the frame, a transversely disposed roller positioned to coact with the coin holding roller to position coins on the stand, means adjusting the position of the transversely disposed roller, and means slidably mounted in the rectangular-shaped frame for clamping

rolls of coins on the stand with the said rolls of coins adapted to roll for wrapping.
